INVENTOR.

Guy B. Fitz
By his Attorney,
Nelson W. Howard

UNITED STATES PATENT OFFICE.

GUY B. FITZ, OF AUBURN, MAINE, ASSIGNOR TO FITZ-EMPIRE DOUBLE PIVOT LAST COMPANY, OF AUBURN, MAINE, A CORPORATION OF MAINE.

HINGE LAST.

Application filed May 15, 1928. Serial No. 278,005.

This invention refers to hinge lasts.

There is a considerable demand in the trade for a hinge last which will be impositively locked in both extended and collapsed position, that is, which can be moved by pressure from one position to the other, but will not of itself tend to move from one position to the other, and at least requires a considerable pressure to move it from extended position.

10 All such lasts heretofore furnished to the trade have been subject to various disadvantages. Either the spring, which is a necessary component of the impositive locking means, has been located so high in the forepart of the last that the thin cone or instep portion of the forepart was unduly weakened, or, on the other hand, the lasts in which the spring was inserted in the lower thicker portion of the forepart have been very complicated and expensive.

15 It is an important object of the present invention to provide a last of the type described which shall obviate those and other disadvantages. To this end I have provided a last in which the heelpart and forepart are connected by two simple flat links lying one above the other with a spring-pressed plunger cooperating with a notch or cam surface on the lower link to hold the last impositively in either extended or collapsed position. The spring is thus located in the lower part of the last where there is room for it, and the link structure is cheap and strong and has proven very efficient in use.

20 35 This and other features of the invention will be better understood from the following description of a preferred embodiment thereof illustrated in the drawings, in which

Fig. 1 shows the last in extended position, and

Fig. 2 shows the last in collapsed position.

In the last illustrated the forepart 10 and heelpart 12 are separated by a cut of any convenient formation, though preferably having a substantially horizontal shoulder 14 on the forepart extending into the heelpart to aline the last parts properly and to prevent relative twisting in use. The last parts are united by a lower link 16 anchored in the heelpart and forepart, respectively, by hinge pins 18, 20, and by an upper link 22 similarly anchored by hinge pins 24, 26. These links are located in thin kerfs in the last parts, one directly

above the other, so that the amount of wood removed is minimized.

55 The lower link 16 has a notch or cam surface 28 on its front end cooperating with a pin 30 which is impelled rearwardly by a spring 32 in a hole 34 in the forepart 10. This hole 34 is located, as seen in the drawing, 60 substantially below the upper thin portion of the forepart, where the wood is thick enough to provide room for it, and thus the last is not unduly weakened by the insertion of the spring.

65 In Fig. 2 the last is shown in collapsed position. In the collapsing movement, which is accomplished by pressure alone, the links and heelpart turn upwardly and the notch 28 rides over the pin 30, which comes to rest on the 70 end surface of the link 16 above the notch, thus holding the last in collapsed position by friction and, with the form of link shown, by a slight resilient cam action, since the upper end of the notch 28 is a little farther from the 75 pin 30 than the adjacent end surface of the link 16.

75 The illustrated bonding mechanism comprising the two flat links 16, 22 and the shoulder 14 make the last very strong in resisting 80 twisting stresses. The amount of wood removed to permit the insertion of the hardware is reduced to a minimum and the last is thereby weakened very little by it.

Having thus described my invention, what 85 I claim as new and desire to secure by Letters Patent of the United States is:

1. A hinge last comprising a heelpart and a forepart having a substantially horizontal shoulder on its rear face projecting into a 90 corresponding depression in the front face of the heelpart, the said last parts having kerfs in their meeting faces, two flat links located one directly above the other in the kerfs and each hingedly pinned into each last part, the 95 lower link being located in the lower half of the last and having a cam surface on one of its ends, and a spring-pressed plunger located below the center of the last part to which the cam-surfaced link-end is connected 100 and cooperating with the said link-end to hold the last impositively in collapsed and extended positions.

2. A hinge last comprising a heelpart and a forepart having a substantially horizontal shoulder on its rear face projecting into a cor-

responding depression in the front face of the heelpart, the said last parts having kerfs in their meeting faces, two flat links located one directly above the other in the kerfs and each hingedly pinned into each last part, the lower link being located in the lower half of the last and having a cam surface on its front end, the forepart having a hole located below its

central axis, and a spring-pressed plunger located in the hole and cooperating with the 10 cam-surfaced end of the lower link to hold the last impositively in collapsed and extended positions.

In testimony whereof I have signed my name to this specification.

GUY B. FITZ.
